Primary Examiner — Susan Bennett Hattan*Assistant Examiner* — Elizabeth Sun Ko(74) *Attorney, Agent, or Firm* — Kyle R Satterthwaite; Michael R Williams; Ade & Company Inc.(57) **CLAIM**

The ornamental design for a welding tool pouch, as shown and described.

DESCRIPTION

FIG. 1 is a front left perspective of a welding tool pouch, showing my new design.

FIG. 2 is a front right perspective view thereof;

FIG. 3 is a rear elevational view thereof;

FIG. 4 is a front elevational view thereof;

FIG. 5 is a right elevational view thereof;

FIG. 6 is a left elevational view thereof;

FIG. 7 is a top plan view thereof; and,

FIG. 8 is a bottom plan view thereof.

Broken lines are used to represent stitching, which is not part of the claimed design.
